ACOUSTICAL TILE

Henry A. Sheehan, New York, N.Y., assignor to Allied Chemical Corporation, New York, N.Y., a corporation of New York

Filed Nov. 1, 1963, Ser. No. 77,255

Term of patent 14 years

(Cl. D18—2)

FIG.1.

FIG.2.

FIGURE 1 is a plan view of an acoustical tile showing my new design.

FIGURE 2 is an enlarged fragmentary cross-sectional view of FIGURE 1 taken on line 2—2 thereof.

I claim:

The ornamental design for an acoustical tile, substantially as shown.
